FIG. 1FIG. 2

FIG. 1 is a perspective view of a game table showing my new design.

FIG. 2 is a top plan view thereof.

FIG. 3 is a cross-sectional view taken along the line 3-3 of FIG. 1.

FIG. 4 is a cross-sectional view taken along the line 4-4 of FIG. 1.

The characteristic feature of my design resides in the provision of three perforations of differing diameters on each side of the goal pocket on each end of the game table; each perforation extending through its respective table end near a corner thereof; being flush with the adjacent upturned corner of the playing field and leading to a ball-retaining pocket mounted on the exterior surface of its respective table end.

This is a continuation-in-part of co-pending application Ser. No. D-21,724, filed Mar. 3, 1970, and entitled Game Table, now abandoned.

I claim:

The ornamental design for a game table, as shown and described.
